UNITED STATES PATENT OFFICE.

MERRILL L. JENKINS, OF HARVEY, ILLINOIS, ASSIGNOR TO BUDA FOUNDRY & MANUFACTURING COMPANY, OF CHICAGO, ILLINOIS, A CORPORATION OF ILLINOIS.

LIFTING-JACK.

No. 923,657.

Specification of Letters Patent.

Patented June 1, 1908.

Application filed October 1, 1908. Serial No. 455,673.

To all whom it may concern:

Be it known that I, MERRILL L. JENKINS, a citizen of the United States, residing at Harvey, in the county of Cook and State of Illinois, have invented certain new and useful Improvements in Lifting-Jacks, of which the following is a specification.

The invention relates to jacks and particularly to those of the screw type. The invention has for its primary objects; the provision of an improved form of anti-friction support for the cap; and the provision of an improved arrangement for mounting the bearing plates employed and distributing 10 the wear on such bearing plates to the end that an increase in durability and ease of operation be secured. Certain embodiments of the invention are illustrated in the accompanying drawings, wherein:

20 Figure 1 is a longitudinal section through the jack,

Figure 2 is a plan view of the ball retainer employed,

25 Figure 3 is a side elevation of the retainer, and

Figures 4 and 5 are modified forms of retainers which may be employed.

Referring first to the general arrangement as shown in Figure 1, the principal parts 30 may be enumerated as follows, 1 is the base or frame of the jack, 2 is the operating nut for the spindle, 3 is the lifting spindle threaded through the nut 2, 4 is the lifting member mounted for reciprocation upon the frame 1 and provided with a foot 5 and a cap 6, which cap is screw threaded into the top of the lifting member as illustrated, 7 is a bearing plate secured to the lower face of the cap, 8 is the operating gear mounted 35 upon the upper portion of the spindle 3, 9 is a bearing plate mounted upon the upper face of the gear 8 and secured so as to turn therewith, 10 are balls interposed between the bearing plates 7 and 9, 11 is a retainer for the balls (shown in detail in Figures 2 and 3), 12 is an operating pinion carried by the shaft 13, which shaft is journaled in a member 14 carried by the lifting member 4, and 40 15 is the holding pawl.

50 It will be noted that the gear 8 has a projecting hub portion 16 upon which the bearing plate 9 and retainer 11 are centered, and that the upper bearing plate 7 is centered about the upper end of the spindle 3. By 55 this arrangement the spindle 3 constitutes in

effect the centering member of both the bearing plates and retainer, and as a result these parts are securely maintained in their proper relative positions. It will also be noted that the bearing may be very conveniently and easily exposed by merely unscrewing the cap 5 and removing it with its attached bearing plate 7. The cap is prevented from accidental unscrewing by means of the set screw 17. A hole 18 is provided through the cap for 60 the application of a lubricant. It will be seen that the spindle is securely guided both beneath the nut 2 in the frame 1, and above such nut at the extreme upper end of the spindle where such spindle engages the bearing plate 7.

In order to properly distribute the load over the bearing plates, the retainer illustrated in enlarged detail in Figs. 2 and 3 is 65 preferably employed. This retainer is centered about the projecting portion of the hub 16 of the gear 8, and as illustrated is provided with three rows of ball holes. Each of these rows of holes is divided into two sets of holes lying on the center lines 19 70 and 20, 21 and 22, and 23 and 24. It will be noted that these center lines for each row of holes are offset from each other only a slight 75 distance, the purpose being to make the balls of each row run in two separate courses 80 and 20, 21 and 22, and 23 and 24. It will be noted that these center lines for each row of holes are offset from each other only a slight 85 distance, the purpose being to make the balls of each row run in two separate courses spaced only a slight distance from each other. The object achieved is a distribution 90 of the wear over a larger area thereby increasing the durability of the bearing plate. If desired the rows might be provided with a greater number of center lines than two, thus still further distributing the wear. This 95 construction greatly increases the life of the bearing without increasing the cost thereof or materially increasing the space occupied by the bearing, as it will be seen that the row of balls having the two courses occupies only a slightly greater amount of space than would a single row of balls in exact circular alinement. This bearing construction is also 100 especially advantageous in a jack as the loads carried are very great and the tendency where balls are used is to wear grooves in the bearing plate in a short time. The arrangement illustrated in Figures 2 and 3 105 practically doubles the area upon which the weight is borne, and the grooving of the plates is materially lessened.

Figures 4 and 5 illustrate modified forms 110 of retainers, Figure 4 showing a retainer

with two rows of holes each of which rows is divided into two sets, while Figure 5 illustrates a retainer having a single row of holes divided into two sets and adapted to run in two courses. These modified arrangements are suitable where smaller sizes of jacks are constructed. Various other arrangements may be substituted to meet requirements.

Having thus described my invention and illustrated its use, what I claim as new and desire to secure by Letters Patent is the following:—

1. In combination in a jack, a frame provided with a nut, a spindle threaded through the nut, a lifting member mounted for reciprocation upon the frame and having a cap provided upon its under side with a bearing surface, a gear secured to the spindle and having a projecting hub portion, a bearing plate fitting around the hub portion, an annular ball retainer having flanges at its inner and outer peripheries with an interposed perforated plate for engaging the balls, the inner flange of the retainer fitting around the said hub portion, balls interposed between the bearing surface and the bearing plate, and means carried by the lifting member for rotating the gear.

2. In combination in a jack, a frame provided with a nut, a spindle threaded through the nut, a lifting member mounted for reciprocation upon the frame and having a cap provided upon its under side with a bearing surface, a gear secured to the spindle and having a projecting hub portion, a bearing plate fitting around the hub portion, balls interposed between the bearing surface and

bearing plate, and an annular ball retainer comprising a perforated plate for engaging the balls and a flange at the inner edge of the plate fitting around and centered by the said projecting hub portion, the retainer being provided with a row of holes concentrically arranged with respect to the center of the retainer but divided into a plurality of sets of holes, the holes of each set being slightly out of circular alinement with the holes of each other set, and means carried by the lifting member for rotating the gear.

3. In combination in a jack, a frame provided with a nut, a spindle threaded through the nut, a lifting member mounted for reciprocation upon the frame and having a cap provided on its under side with a bearing surface, a gear secured to the spindle and carrying a bearing surface upon its upper face in opposition to the other bearing surface, balls interposed between the surfaces, a retainer for the balls provided with a plurality of rows of holes concentrically arranged with respect to the center of the retainer, each of which rows is divided into a plurality of sets of holes, the holes of each set being in circular alinement, but slightly out of circular alinement with the holes of each other set, and means carried by the lifting member for rotating the gear.

In testimony whereof I have hereunto signed my name in the presence of the two subscribed witnesses.

MERRILL L. JENKINS.
